MACHINE FOR STRAIGHTENING
METAL DRUMS

Eugene A. Schlank, Cincinnati, Ohio

Application August 27, 1951, Serial No. 243,798

3 Claims. (Cl. 153—61)

1

This invention relates to a device for straightening metal drums.

An object of this invention is to provide a device which will straighten metal drums having a cylindrical side wall and formed with a pair of spaced beads between the ends thereof.

Another object of this invention is to provide a drum straightening device which will not only straighten the side wall of the drum and also straighten the annular beads on the side wall, but will also straighten the flange or chime at the bottom of the drum.

A further object of this invention is to provide a device of this kind which is simple in construction and is capable of handling drums of different diameters.

With the above and other objects in view, my invention consists in the arrangement, combination and details of construction disclosed in the drawings and specification, and then more particularly pointed out in the appended claims.

In the drawings,

Figure 1 is a detail side elevation of a drum straightening machine constructed according to an embodiment of this invention.

Figure 2 is a detail front elevation of the device,

Figure 3 is a sectional view taken on the line 3—3 of Figure 1,

Figure 4 is a fragmentary sectional view taken on the line 4—4 of Figure 1,

Figure 5 is a fragmentary sectional view taken on the line 5—5 of Figure 2,

Figure 6 is a fragmentary sectional view taken on the line 6—6 of Figure 1,

Figure 7 is a fragmentary sectional view taken on the line 7—7 of Figure 1.

Referring to the drawings, the numeral 10 designates generally a frame structure which includes a base 11 having secured thereto upright frame members 12 and 13. The frame members 12 and 13 have secured thereto forwardly extending tubular frame members 15 which are disposed in parallel relation with respect to the base 11 and project forwardly from the forward frame member 13.

An upper pair of roller carrying shafts 16 are journaled through the frame members 12 and 13, being rotatably supported from bearings 17 carried by an intermediate horizontal frame member 18. The shafts 16 have secured thereto rollers 19, 20 and 21 and intermediate beaded rollers 22 and 23 are disposed between adjacent pairs of rollers 19, 20 and 21. The beaded rollers 22 and 23 are adapted to engage on the concave

2

inner side of a bead formed in the drum between the ends of the drum so that the bead will be re-established or straightened.

One of the shafts 16 has secured thereto a sprocket 24 about which a driving chain 25 engages and the chain 25 engages about a lower driving sprocket 26 which is connected with a motor or power member 27. The two shafts 16 at their rear ends have secured thereto sprockets 28, and a chain 29 is trained about the two sprockets 28 so that the two shafts 16 will be rotated in the same direction and at the same speed.

An intermediate idler roller 30 is rotatably carried by a plate 31 which is connected between the forward ends of the frame bars 15 and the roller 30 is adapted to engage between the two forward rollers 21 as shown in Figure 2. A pair of relatively small idler or bracing rollers 32 are also rotatably carried by the plate 31 and engage the forward rollers 21 outwardly from the point of contact of intermediate roller 30 with the rollers 21.

A lower pair of shafts 33 are disposed below the upper shafts 16 and are fixedly secured to an

hinge plate or leaf 34 which is rockably carried by a horizontally disposed bar 35 fixed between the upright sides of the rear frame 12. The leaf 34 is secured to a shaft 33 by means of a U-shaped clamp 36 so that shaft 33 will be held against rotation and will be permitted to have vertical rocking movement as will be hereinafter described.

The forward ends of the non-rotatable shafts 33 are secured to a horizontally disposed plate 37 and the plate 37 has extending forwardly therefrom a pair of ears 38 between which the upper end of a plunger rod 39 is adapted to be rockably mounted. The rod 39 is secured to a piston 40 slidably in a pressure cylinder 41 and the cylinder 41 is adapted to be connected to a source of pressure supply by means of pipes 42 and 43.

Each shaft 33 has rotatably mounted thereon rollers 44, 45 and 46, and also has mounted between pairs of these rollers grooved rollers 47 and 48. The grooved rollers 47 and 48 cooperate with the beaded rollers 22 and 23 in effecting the straightening of the bead in the cylindrical wall of a drum generally designated as D. The forward roller 46 of each shaft 33 is formed with an offset 49 within which the flanged outer end of the drum is adapted to engage. The flange or chime of the drum is straightened by means of a bevelled roller 51 rotatably carried by a shaft 52. The shaft 52 is fixed to a rock lever 53 which

is rockably mounted on a pivot 54 carried by an upright support 55.

The roller 51, as shown in Figure 2, is disposed between the two lower rollers 46 and is moved forwardly to operative position with upward movement of plate 37 and shafts 33 by means of a link 56 pivotally secured to the ears 38. The upper end of link 56 is pivotally connected to a depending arm 56a which extends downwardly from lever 53.

In the use and operation of this device, the drum will have one head thereof removed and the drum is then extended over rollers 21, 20 and 19 respectively. At this time the shafts 33 will be in dotted line position shown in Figure 1. The shafts 33 are then raised by upward movement of piston 40 so that rollers 44, 45 and 46 will engage the outer side of the cylindrical drum wall and press the drum against the inner or upper rollers 19, 20 and 21. As the side of the drum is being straightened by rolling contact with the upper and lower rollers, the chime or flange at the bottom of the drum will also be straightened by the bevelled roller 51.

I do not mean to confine myself to the exact details of construction herein disclosed, but claim all variations falling within the purview of the appended claims.

What I claim is:

1. A drum straightening device comprising a base, a pair of upright frame members carried by said base adjacent the rear thereof, a pair of shafts rotatably carried by said frame members and disposed in parallel relation with respect to said base, rollers fixed on said shafts, a second pair of shafts disposed below said first pair of shafts, means rockably supporting one end of said second pair of shafts from said frame members, rollers rotatably carried by said second pair of shafts, a chime engaging roller rockably carried by said base between said second pair of shafts, means engaging the forward ends of said second pair of shafts for moving said second pair of shafts toward or away from said first pair of shafts, and means connected with said last-mentioned means for rocking said chime roller to operative position with rocking of said second pair of shafts to operative position.

2. A drum straightening device comprising a base, upright frame means at one end of said base, horizontally disposed frame means extending forwardly from said upright frame means, an upper roller shaft rotatably carried by said upright frame means and extending forwardly therefrom parallel with said horizontal frame means, a lower pair of shafts, means rockably supporting the rear ends of said lower shafts

5
10

from said frame means, rollers carried by said upper and lower shafts, means engaging the forward ends of said lower shafts for rocking the latter from a lower inoperative position to an upper operative position, a chime engaging roller, means rockably supporting said chime engaging roller between the forward ends of said lower shafts, means connecting said chime roller supporting means with said shaft rocking means for rocking movement therewith, and a bracing roller carried by the forward portion of said horizontal frame means for bracing said upper shaft.

3. A drum straightening device comprising a base, upright frame means at one end of said base, horizontally disposed frame means extending forwardly from said upright frame means, an upper pair of roller shafts rotatably carried by said upright frame means and extending forwardly therefrom parallel with said horizontal frame means, a lower pair of shafts, means rockably supporting the rear ends of said lower shafts from said frame means, rollers carried by said upper and lower shafts, hydraulic piston means engaging the forward ends of said lower shafts for rocking the latter from a lower inoperative position to an upper operative position, a chime engaging roller, means rockably supporting said chime engaging roller between the forward ends of said lower shafts, means including a link pivotally connected at one end to said chime roller and pivotally connected at its other end to said shaft rocking means for rocking movement therewith, and bracing rollers carried by the forward portion of said horizontal frame means for bracing said upper shafts.

EUGENE A. SCHLANK.
